UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A BOILER-HEAD.

SPECIFICATION forming part of Design No. 20,238, dated October 28, 1890.

Application filed October 2, 1890. Serial No. 366,888. Term of patent 7 years.

To all whom it may concern:

Be it known that I, THOMAS I. RANKIN, a citizen of the United States, and a resident of Philadelphia, Pennsylvania, have invented 5 a new and original Design for a Boiler-Head, of which the following is a specification.

My design for a boiler-head is fully illustrated in the accompanying drawings.

The main feature of the design is the series 10 of radiating ribs extending from a central point to an outer band having protuberances thereon.

In the accompanying drawings, Figure 1 is 15 a plan view illustrating my new design for a boiler-head; and Fig. 2 is a sectional view on the line 1 2, Fig. 1.

In the head are a series of orifices *a*, and at the center is a central dome *B*, slightly rounded, and radiating from this dome are a series of tapered and rounded ribs *D*, extending to 20 a circular band *E*, having at intervals in its surface protuberances *e*.

I claim—

The design for a boiler-head, substantially 25 as shown and described.

In testimony whereof I have signed my name to this specification in the presence of two subscribing witnesses.

THOMAS I. RANKIN.

Witnesses:

HENRY HOWSON,
HARRY SMITH.
